(57) **CLAIM**

We claim the ornamental design for a fall protection sleeve, as shown and described.

DESCRIPTION

FIG. 1 is a first perspective view of a fall protection sleeve showing our new design;

FIG. 2 is a second perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof; and,

FIG. 9 is another perspective view thereof, shown attached to a cable.

The broken lines adjacent shaded areas depict boundaries of the claim and form no part of the claimed design. All other broken lines illustrate unclaimed portions of the fall protection sleeve and form no part of the claimed design.
